UNITED STATES PATENT OFFICE.

GUILLERMO A. FARINI, OF TORONTO, ONTARIO, CANADA, ASSIGNOR OF
ONE-HALF TO RENSSELAER HUNT, OF HAMILTON, CANADA.

BOAT.

No. 852,380.

Specification of Letters Patent.

Patented April 30, 1907.

Application filed August 22, 1906. Serial No. 331,573.

To all whom it may concern:

Be it known that I, GUILLERMO ANTONIO FARINI, a subject of the King of Great Britain, and a resident of Toronto, in the county 5 of York and Province of Ontario, Canada, have invented new and useful Improvements in Boats, of which the following is a specification.

My invention relates to improvements in 10 boats, and consists principally of a boat of single tube construction from stem to stern.

The boat has one or more decks, and is strengthened by a number of longitudinal 15 **I** beams rigidly secured to the inner sides of the boat, a proper distance apart, and extending the length of the boat. Suitable steel girders are secured to the **I** beams referred to, and at proper distances apart.

The boat is provided with upper and lower 20 decks in the tube, and supported by suitable vertical walls or pillars and brackets.

The object of my invention is to provide a single tube boat comprising a single shell, of steel construction, with decks inside of the 25 tube, all suitably supported and braced together for strength and stability and means to prevent the cargo from shifting. I attain this object by the mechanism illustrated in the accompanying drawing in which:—

30 Figure 1, is a longitudinal elevation of a single tube boat. Fig. 2, is an enlarged cross section of the same. Fig. 3, is an enlarged part of Fig. 2, of the drawing, showing a part of the tubular shell, the **I** beams and 35 the girders.

In the drawing, the single tube, or shell of the boat, is indicated by **A**, and is of suitable end shape.

B, indicates a number of **I** beams which 40 extend longitudinally in the boat, and are rigidly secured to the inner sides thereof, at proper distances apart.

C indicates straight girders arranged in circumferential sets at proper distances apart; 45 and each girder is secured at one end to the outer edge of one beam **B**, at its center to the inner edge of the next, and at its other end to the outer edge of the next beam. Thus the beams form struts and the girders trusses of 50 a light framework which firmly braces the tubular shell on its interior, while occupying a minimum of space therein and requiring

no inner shell between which and the hull moisture might accumulate or vermin thrive. By preference the girders of one set are in 55 alternated relation to those of the next, so that the struts of one set will stand between the ends of the trusses of the sets adjacent. This gives great strength to the hull against torsion and external pressure, and yet leaves 60 storage space between the sets of girders. The **I**-beams also prevent the shifting of cargo.

E, is an upper deck in the boat, and **F**, is a lower and similar deck both of which extend 65 to the inner sides of the shell **A**, and secured thereto. The lower deck **F**, is partially supported by pillars or walls **2**, which extend from the underside of the deck to the shell **A**. The upper deck **E**, is partially supported 70 from the lower deck by centrally located pillars, or wall **3**, and by suitable stay-brackets **4**, which extend from said deck to the sides of the shell **A**. The wall **3**, prevents the cargo from shifting in the boat. 75

The upper part of the shell **A**, is provided with a promenade deck **6**, with railing **7**, and central hatchway **8**, the whole supported by vertical walls **9**, on the shell **A**.

The principal and important elements in 80 this invention are, a single tubular boat with longitudinal **I** beams **B**, rigidly secured to the inner sides thereof, and girders **C**, rigidly secured to the beams **B**, together with upper and lower decks in the boat, and means for 85 supporting the decks.

The framework composed of beams and girders arranged and connected as above set forth and rigidly secured within the shell strengthens the hull against pressure from 90 within, such as occasioned by the decks, machinery, cargo, and passengers, and hence the employment of this form of braces within the shell of a tubular boat serves a purpose which they would not have if used in roofs 95 where there is no pressure from within.

What I claim as my invention and desire to secure by Letters Patent, is:—

1. In boat construction, a single tubular shell, longitudinal **I**-beams therein, and 100 spaced straight girders each passing centrally over the inner edge of one beam and connected with the outer edges of the two beams on either side thereof.

2. In boat construction, a single tubular shell, circumferential sets of girders therein forming trusses, and longitudinal beams in the shell forming struts to said trusses.
- 5 3. In boat construction, a single tubular shell, circumferential sets of girders therein forming trusses, and longitudinal beams in

the shell forming struts to said trusses, the girders of one set being in alternated relation to those in the next.

G. A. FARINI.
